[57] **CLAIM**

The ornamental design for a combined box sealing clip and handle, substantially as shown and described.

DESCRIPTION

FIG. 1 is a top perspective view of a combined box sealing clip and handle showing my new design;

FIG. 2 is a front elevational view on an enlarged scale broken away for convenience of illustration;

FIG. 3 is a top plan view thereof broken away for convenience of illustration;

FIG. 4 is a bottom view thereof broken away for convenience of illustration;

FIG. 5 is a left end elevational view thereof;

FIG. 6 is a right end elevational view thereof; and

FIG. 7 is a top perspective view of FIG. 1 in an operative condition.
